UNITED STATES PATENT OFFICE

113,612

DESIGN FOR A KNITTED FABRIC

David Siegel, Commack, N. Y.

Application September 21, 1938, Serial No. 80,026

Term of patent 14 years

To all whom it may concern:

Be it known that I, David Siegel, a citizen of the United States, residing at Commack, Long Island, in the county of Suffolk and State of New York, have invented a new, original, and ornamental Design for Knitted Fabrics, of which the following is a specification, reference being had to the accompanying drawing, forming a part thereof, in which the figure is a plan view of a portion of the fabric, showing my design.

The design consists of sizable openings ar-

ranged in blocks, with zones of imperforate cloth extending crosswise of the piece between rows of blocks and with longitudinal zones between longitudinal rows of blocks, the longitudinal zones being imperforate except for a row of openings between a pair of adjacent blocks.

I claim:

The ornamental design for a knitted fabric, as shown and described.

DAVID SIEGEL.
